CLAIM

The ornamental design for a handle for hand held tools, as shown and described.

DESCRIPTION

The file of this patent contains at least one drawing executed in color. Copies of this patent with color drawings will be provided by the United States Patent and Trademark Office upon request and payment of the necessary fee.

FIG. 1 is a top, front and right side perspective view of a handle for hand held tools in the colors red and black showing the new design;

FIG. 2 is a front elevational view of the design of FIG. 1 in the colors red and black;

FIG. 3 is a right side elevational view of the design of FIG. 1 in the colors red and black;

FIG. 4 is a rear elevational view of the design of FIG. 1 in the colors red and black;

FIG. 5 is a left side elevational view of the design of FIG. 1 in the colors red and black;

FIG. 6 is a top plan view of the design of FIG. 1 in the colors red and black; and,

FIG. 7 is a bottom plan view of the design of FIG. 1 in the colors red and black.
